UNITED STATES PATENT OFFICE.

CLARENCE M. ELLINGER AND LEON KOPCZYNSKI, OF BOSTON, MASSACHUSETTS; SAID KOPCZYNSKI ASSIGNOR TO SAID ELLINGER.

BUILDING STRUCTURE.

SPECIFICATION forming part of Letters Patent No. 743,262, dated November 3, 1903.

Application filed May 16, 1903. Serial No. 157,430. (No model.)

To all whom it may concern:

Be it known that we, CLARENCE M. ELLINGER and LEON KOPCZYNSKI, citizens of the United States, residing at Boston, in the county of Suffolk and State of Massachusetts, have invented certain new and useful Improvements in Building Structures, of which the following is a specification.

This invention relates to improvements in fireproof building structures of the kind shown in our pending application, Serial No. 137,843; and it consists in improved means for connecting and tying the metal framework of the structure and in an improved arrangement of the floor and column rods.

In the accompanying drawings, Figure 1 is a side view of the framework in a portion of a beam and column, the inclosing body of cement being indicated in outline. Fig. 2 is a top plan view of the floor-rods adjacent to and over the beam. Fig. 3 is a horizontal section through the column. Fig. 4 is a section on the line 4 4 of Fig. 1. Fig. 5 is a section on the line 5 5 of Fig. 1. Figs. 6, 7, and 8 are sections on the lines 6 6, 7 7, and 8 8, respectively. Fig. 9 is a detail showing one of the loops or ties which connect adjacent column-rods, and Fig. 10 is a perspective view of a modified form of tie.

Referring to the drawings, A, B, and C indicate parts of a column, a beam, and a floor, respectively, these elements of the structure being formed integrally. The column consists of a series of vertically-arranged metal rods, between and around which the cemented material is molded. In the drawings twelve vertically-arranged rods (indicated by the numerals 1 to 12, inclusive) are shown, these rods being arranged in the form of a hollow square. A greater or less number of rods will be used, according to the load which the column is required to carry. The column-rods are braced at suitable intervals by groups of ties D. (Shown in Figs. 1 and 3.) The pairs of rods 2 9, 3 8, 12 5, and 11 6, standing opposite to one another in the hollow square, are tied together by strips of metal a, bent into the form of loops and extending around the rods. The end portions of each loop overlap one another, and the ex-

tremities a' of the strip are bent out of line with the adjacent portions of the strip in order to anchor the ends in the cement. The adjacent rods in the series are also tied together by similar shorter loops b, having outwardly-turned extremities b'. Thus the adjacent pairs of rods 1 2, 2 3, 3 4, 4 5, &c., are tied by separate loops b. A chain of ties thus connects the entire series of rods. These groups of ties brace the column-rods laterally and prevent any spreading tendency.

The framework of the beam comprises several parallel series of tension-rods c c', arranged longitudinally throughout the lower part of the beam, and the number of series of rods depends upon the width of the beam. Each rod extends across one span of the beam between adjacent columns or supports, and the ends 13 of the rods are bent and hooked around the column-rods at the farther side of the column. Thus in the drawings the tension-rods c at the right of the column are hooked around the column-rods 10, 11, 12, and 1, respectively, at the left side of the column, while the tension-rods c' in the span at the left of the column are hooked around the rods 4 to 7, inclusive, at the right of the column. The tension upon the beam-rods therefore tends to force the column-rods toward one another. As the cement withstands great pressure, the column-rods are held immovable by the body of cement between them.

Above the straight tension-rods c c' are arranged in substantially the same vertical planes a corresponding number of rods d d', which rest upon the rods c c' in the central parts of the spans and adjacent to the columns or supports rise gradually into the upper portion of the beam. The ends 14 of these rods, as shown, are bent and hooked around the rods in the column in the same manner as that in which the lower tension-rods are connected to the column-rods. Above the inclined ends of the rods d d' are arranged short horizontal rods e, having their ends 15 turned downwardly to anchor the rods in the cement. These rods e extend through the line of the column in substantially the same vertical plane as the tension-rods above mentioned, and they extend for 100

a short distance at each side of the column to strengthen the beam against shearing stresses adjacent to the column.

The rods in the lower part of the beam are 5 tied to the upper portions of the beam by means of ties *f*, each consisting of a metal strip folded or doubled back and forth upon itself a number of times, the number of folds varying according to the number of rods. 10 These ties are arranged at suitable intervals throughout the beam. The end portions 15 of the ties terminate in the upper part of the beam, and the alternate bends 17 in the ties extend beneath the rods *c*, the intermediate portions or double folds of the ties between alternate bends extending into the upper part 20 of the beam. The ends of the rods *e* in the upper portion of the beam are connected to the lower part of the beam by ties *f'*, Fig. 7, 25 which are the same as the ties *f*, Fig. 6, except that they are inverted with respect thereto. These ties prevent the rods from yielding or springing and also are found very effective in preventing any tendency of the beam to split longitudinally. The ends of 30 the ties are preferably bent out of line with the adjacent portions of the tie, as shown, in order to anchor said ends in the cement.

In Fig. 10 we have shown a modified form 35 of tie, consisting of two parallel steel wires or rods 18, which are laced together throughout their length by a lacing-wire 19 and folded to form a tie of the desired shape. In this form of tie the cement fills the interstices between the wires, and the tie is thus anchored at every point.

A connecting-rod *g* extends throughout the structure above and longitudinally of the beam and in the upper part of the floor. This 40 rod in addition to affording some strength to the beam serves as a means for supporting and connecting the floor-rods *h h'*, which extend through the floor-span at opposite sides of the beam. A rod *g*, it will be understood, 45 is arranged above each beam in a building, and the floor-rods *h h'* are equal in length to the distance between adjacent rods *g* and are provided with bent ends 20, Fig. 7, which are hooked around the rods *g*. These rods, it 50 will be noted from an inspection of Figs. 6 and 7, rise gradually as they approach the beam in the same manner as the tension-rods *d d'* in the beam. Between each series of rods *h h'* is arranged a rod *i*, which extends horizontally through the lower part of the floor beneath the rods *g*. These rods *i* in the 55 floor have the same function as the rods *c* in the beam.

The strips of metal which form the ties 60 may be of any suitable form in cross-section and may conveniently be made from round or square bars of steel or other metal instead of being made from flat bars or bands, and we intend the word "strip" as used in the 65 claims to include bars or bands of any desirable cross-section.

Having described our invention, what we

claim, and desire to secure by Letters Patent, is—

1. In a building structure, a beam and column composed of a mass of cemented material and a framework of metal rods embedded in said mass, said framework comprising column-rods arranged vertically in the column and extending into the beam, and tension-rods 75 arranged longitudinally in the beam and having bent ends which are hooked around the column-rods.

2. In a building structure, a beam and column composed of a mass of cemented material and a framework of metal rods embedded in said mass, said framework comprising column-rods arranged vertically in the column and extending into the beam, and a pair of straight tension-rods arranged longitudinally 85 in the lower part of the beam at opposite sides of the column and having bent ends which are hooked around the column-rods.

3. In a building structure, a beam and column composed of a mass of cemented material and a framework of metal rods embedded in said mass, said framework comprising column-rods arranged vertically in the column and extending into the beam, and a pair of rods extending through the lower part of the 95 beam at opposite sides of the column, thence rising gradually adjacent to the column into the upper part of the beam and having bent ends which are hooked around the column-rods.

4. In a building structure, a beam and column composed of a mass of cemented material and a framework of metal rods embedded in said mass, said framework comprising column-rods arranged vertically in the column 105 and extending into the beam, a pair of straight tension-rods arranged longitudinally in the lower part of the beam at opposite sides of the column, and a pair of rods arranged above said tension-rods and extending through the 110 lower part of the beam at opposite sides of the column, thence rising gradually adjacent to the column into the upper part of the beam, said rods in the beam having bent ends which are hooked around the column- 115 rods.

5. In a building structure, a beam composed of a mass of cemented material and a framework of metal rods embedded in said mass, said framework comprising a plurality of 120 rods arranged longitudinally in the lower part of the beam, a plurality of rods arranged in the upper part of the beam in the same vertical planes as the lower rods, and ties consisting of strips of metal folded back and 125 forth upon themselves a plurality of times, said ties being arranged transversely in the beam and having their lower bends extending beneath the lower rods and an intermediate series of double folds extending upwardly into the beam between said bends.

6. In a building structure, a beam composed of a mass of cemented material and a framework of metal rods embedded in said mass,

- said framework comprising a plurality of rods arranged longitudinally in the lower part of the beam, a plurality of rods arranged in the upper part of the beam in the same vertical planes as the lower rods, and ties consisting of strips of metal folded back and forth upon themselves a plurality of times, said ties being arranged transversely in the beam and having their upper bends extending over the upper rods and an intermediate series of double folds extending downwardly into the beam between said bends.
7. In a building structure, a beam composed of a mass of cemented material and a framework of metal rods embedded in said mass, said framework comprising a plurality of rods arranged longitudinally in the lower part of the beam, a plurality of rods arranged in the upper part of the beam in the same vertical planes as the lower rods, and ties consisting of strips of metal folded back and forth upon themselves a plurality of times, said ties being arranged transversely in the beam, and certain of said ties having their alternate bends extending beneath the lower rods and other ties having their alternate bends extending over the upper rods, each tie having several double folds arranged vertically in the beam.
- 30 8. In a building structure, such as a beam, consisting of a mass of cemented material and a framework of metal rods longitudinally arranged therein, a tie or band consisting of a pair of parallel wires or rods connected together by wire lacing, said strip or band being folded back and forth upon itself a plurality of times and arranged transversely of the structure.
9. In a building structure, a beam and floor composed of a mass of cemented material and a framework of metal rods embedded in said mass, said framework comprising a metal connecting-rod extending longitudinally through the beam, in line with the floor, and floor-rods extending through the floor at opposite sides of the beam, said floor-rods having their adjacent ends secured to said connecting-rod.
10. In a building structure, a beam and floor composed of a mass of cemented material and a framework of metal rods embedded in said mass, said framework comprising a metal connecting-rod extending longitudinally through the beam, in line with the floor and floor-rods extending through the floor at opposite sides of the beam, said floor-rods having bent ends which are hooked around said connecting-rod.
11. In a building structure, a beam and floor composed of a mass of cemented material and a framework of metal rods embedded in said mass, said framework comprising a connecting-rod extending longitudinally through the beam, in line with the floor, floor-rods extending through the floor below said connecting-rod, and other floor-rods extend-

ing through the floor at opposite sides of the beam, said latter rods terminating above the beam and having their ends secured to said connecting-rod.

12. In a building structure, a beam and floor composed of a mass of cemented material and a framework of metal rods embedded in said mass, said framework comprising a connecting-rod extending longitudinally through the beam, in line with the floor, floor-rods extending through the floor below said connecting-rod, and other floor-rods extending through the floor at opposite sides of the beam, said latter rods terminating above the beam and having bent ends which are hooked around said connecting-rod.

13. In a building structure, a beam and column composed of a mass of cemented material and a framework of metal rods embedded in said mass, said framework comprising rods arranged vertically in the beam in line with the column, and tension-rods extending longitudinally in the beam at opposite sides of the column, said tension-rods having overlapping ends connected to said vertically-arranged rods at opposite sides of the column.

14. In a building structure, a beam and column composed of a mass of cemented material and a framework of metal rods embedded in said mass, said framework comprising column-rods arranged vertically in the column and extending into the beam, and tension-rods extending longitudinally in the beam at opposite sides of the column, the ends of said tension-rods being secured to the column-rods.

15. In a building structure, a beam and column composed of a mass of cemented material and a framework of metal rods embedded in said mass, said framework comprising column-rods arranged vertically in the column and extending into the beam, and tension-rods extending longitudinally in the beam at opposite sides of the column, said tension-rods having overlapping ends connected to the column-rods at opposite sides of the column.

16. In a building structure, a beam and column composed of a mass of cemented material and a framework of metal rods embedded in said mass, said framework comprising column-rods arranged vertically in the column and extending into the beam, and tension-rods extending longitudinally in the beam at opposite sides of the column, said tension-rods having overlapping bent ends which are hooked around the column-rods at opposite sides of the column.

In testimony whereof we affix our signatures in presence of two witnesses.
